(57) **CLAIM**

The ornamental design for an emergency light as shown and described.

DESCRIPTION

FIG. 1 is a front and bottom perspective view showing of an emergency light showing my new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view showing of the emergency light in use state; and,

FIG. 10 is a rear perspective view showing of the emergency light in use state.

The broken lines in the figures illustrate portions of the emergency light that form no part of the claimed design.
